(57) CLAIM

The ornamental design for a corner panel for a spa, as shown and described.

DESCRIPTION

FIG. 1 is a top, front, left perspective view of the corner panel for a spa, shown in condition of use and affixed to a spa;

FIG. 2 is second top, front, left perspective view of the corner panel for a spa of FIG. 1, shown enlarged for clarity of disclosure;

FIG. 3 is a top plan view thereof;

FIG. 4 is a front elevation view thereof; and,

FIG. 5 is a left side elevation view thereof.

In the drawings, the equal-length broke lines depict portions of the corner panel for a spa that form no part of the claimed design. In FIG. 1, the equal-length broke lines showing a spa depict environmental structure that form no part of the claimed design. All broke lines form no part of the claim.

1 Claim, 3 Drawing Sheets
